ABSTRACT: A unique stepped end bag of the type having a tubular body formed from a plurality of superposed plies of bag-forming material terminating at different points to form stepped ends featuring a component arrangement which provides alternate grasping notches and tabs which facilitates the use of bottoming equipment to close and seal the ends of the bag that was previously limited to use on flush-cut bags. The alternate notches and tabs are formed in the inner ply to allow the grasping fingers on bottoming equipment to grasp and separate the opposite sides of the bag ends so that the ends can be automatically glued and folded into sealed relationship.

STEPPED END BAG

BACKGROUND OF THE INVENTION

This invention relates to a unique stepped end bag configuration and, more particularly, a stepped end paper bag featuring a unique component arrangement which provides alternate grasping tabs and notches to facilitate the use of bottoming equipment that was previously limited to use on flush-cut type bags.

Paper bags have historically been constructed from separate layers or plies of paper. A standard type of paper bag has been the flush-cut type where a tubular configuration is formed of several layers of paper, each of the layers being of the same length and having their ends cut flush with each other. On opposite sides of this type of bag alternate notches were formed to facilitate the use of bottoming equipment to seal the ends of these paper bags. These flush-cut bags were fed lengthwise into standard bottoming equipment, such as the well-known "Coty Bottomer" manufactured by Coty Manufacturing Company, which have gripping fingers which separate one side of the bag from the other by grasping it in the area of the notches. The bottoming equipment then applied adhesive to the ends of the bag and folded the ends into sealed engagement. This finger-grasping type bottoming equipment has heretofore been limited to use on flush-cut bags with notches cut completely through the several plies of paper forming the end of the bag.

In recent years, the stepped end paper bag has become increasingly popular due to the considerable savings of paper used in each individual bag. The stepped end bag is formed from a plurality of layers of paper overlying each other in a tubular configuration as is the flush-cut bag. However, in the stepped end bag, each of the layers of paper has portions removed to form staggered or stepped ends as it has been found that the ends can be folded and sealed without the necessity of having each layer of paper being the same length. The savings of even small amounts of paper material in the ends of the paper bag when multiplied by the tremendous number of paper bags in use today can amount to a considerable decrease in the cost of paper bags. To date, the manufacture of stepped end bags has required the use of a so-called flatbed bottoming machine which requires that the bags be fed in sideways and which uses vacuum attachments to separate the opposite sides of the bag to facilitate the gluing and folding of the ends into a sealed arrangement. Thus, the increased usage of the more economical stepped end bag has resulted in the obsolescence of the older type finger-grasping bottoming equipment used heretofore only on flush-cut bags.

SUMMARY OF THE INVENTION

It is therefore an object of this invention to provide a unique stepped end bag which is adapted to automatically have its ends closed and sealed on the finger-grasping type bottoming equipment used previously only on flush-cut bags. To accomplish this result, this invention provides a stepped end bag formed from three superposed tubular plies of paper attached to each other so that their ends are not coterminous. Alternating notches and tabs are formed on the inner ply of paper so as to provide a space through which the gripping fingers of the older type bottoming equipment may grasp one side of the paper bag so as to separate it from the opposite side and facilitate the application of adhesive and the folding of the two sides together to sealingly close the ends of the bag.

Other objects, features, and advantages of this invention will become obvious to those skilled in the art to which it pertains upon reference to the following detailed description and the drawings illustrating the preferred embodiment thereof.

IN THE DRAWINGS

FIG. 1 is a schematic view of a stepped end paper bag of this invention with its ends separated so that the individual layers can be distinguished.

FIG. 2 is a perspective view of the stepped end bag of this invention.

FIG. 3 is a perspective view of the stepped end bag of FIG. 2 as it is being sealed.

FIG. 4 is a perspective view of the stepped end bag of this invention after it has been completely closed.

DETAILED DESCRIPTION OF THE PREFERRED EMBODIMENT

The drawings illustrate a stepped end paper bag indicated generally by the numeral 10. The stepped end bag 10 is formed from three tubular plies of paper 12, 14, and 16. The inner ply 12 and the middle ply 14 are generally of the same grade of paper, while the outer ply 16 may be of a different grade of paper which is better adaptable for printing purposes. As can be seen in each of the figures, the three layers of paper have been cut to different lengths so that excess paper not needed in the sealing and closing of the ends has been eliminated. As can be seen in FIG. 1, each of the opposite ends of the bag 10 are identical so that the details shown in FIGS. 2-4 of one of the ends and the closing thereof is also applicable to the other end.

As can be seen in FIGS. 2 and 3, the opposite sides of inner layer 12 have been alternately notched so that notches 18 and tabs 20 are formed therein. As can be seen in FIG. 1, the upper side of the inner layer 12 has a notch 18 at one end and a tab 20 at the other end. Alternately, the lower side of the inner ply 12 has a tab 20 at one end and a notch 18 at the other end. It should be understood that the next bag to be formed (not shown) on the tuber will have a tab 20 which has a tab which matches the notch 18 and a notch which mates with the tab 20. As explained earlier, it is the purpose of these alternate notches 18 and tabs 20 to adapt this stepped end bag 10 of this invention for use on a bottoming machine which utilized gripping fingers to separate the opposite sides of the bag to the position shown in FIG. 2. Without these alternate notches 18 and tabs 20, this standard bottoming equipment, formerly useable on only flush-cut bags, would not be able to grasp the opposite sides of the bag so as to separate them for the gluing and folding operations. Once the opposite sides are separated as shown in FIG. 2, adhesive is applied directly to the interior of the multiple layered bag 10 and the ends folded into sealed engagement as shown in the transition from FIG. 3 to FIG. 4. The outer surface of the resulting end of the bag is formed completely by the outer ply 16 which is folded over the middle and inner plies 14 and 12, respectively. The resulting end as shown in FIG. 4 is completely sealed and closed so that the contents cannot escape from the bag 10.

Thus, it is the unique configuration of the stepped end bag of this invention wherein alternate notches 18 and tabs 20 are provided which makes this stepped end bag adaptable to be closed and sealed automatically on the finger-grasping type bottoming equipment formerly useable only on flush-cut bags.

As explained previously, the flatbed-type bottoming equipment presently used with stepped end bags requires that the bag be turned sideways prior to its entrance into the bottoming machine. In contrast to this, the finger-grasping type bottoming equipment will receive a bag lengthwise as it comes off the tuber and, as a result, eliminates the need for equipment to rotate the bag and, therefore speeds up the bottoming operation. Therefore, it should be understood that the unique configuration of the stepped end bag of this invention facilitates the use of finger-grasping type bottoming equipment, heretofore not useable with stepped end bags, and results in an overall increase in the speed of production of stepped end bags.

I claim:

1. A multi-ply stepped end tubular bag adapted to be sealingly closed at its ends by finger-grasping type end closing means, said bag comprising a plurality of superposed tubular plies of bag-forming material, each of said tubular plies having a portion of its end material removed so as to form stepped ends on said tubular plies, the outermost tubular ply being the

shortest of said tubular plies, and the innermost tubular ply being the longest of said tubular plies, and the innermost of said tubular plies having on each end thereof to facilitate the

separation of said ends by said finger-grasping type end-closing means for application of adhesive and folding of said two sides together to sealingly close the ends of said bag.

UNITED STATES PATENT OFFICE
CERTIFICATE OF CORRECTION

Patent No. 3,596,826 Dated August 3, 1971

Inventor(s) William J. Reiselt

It is certified that error appears in the above-identified patent and that said Letters Patent are hereby corrected as shown below:

Column 3, line 3, after the word "thereof", insert
--a single grasping notch and tab formed on opposite
sides thereof--.
